(57) **CLAIM**

The ornamental design for an electric bicycle, as shown and described.

DESCRIPTION

FIG. 1 is a top, front and left side perspective view an electric bicycle showing our new design;

FIG. 2 is a bottom, rear and right side perspective view thereof;

FIG. 3 is a left side elevation view thereof;

FIG. 4 is a right side elevation view thereof;

FIG. 5 is a rear elevation view thereof;

FIG. 6 is a front elevation view thereof;

FIG. 7 is a top plan view thereof;

FIG. 8 is a bottom plan view thereof;

FIG. 9 is an enlarged view of area "9" in FIG. 1;

FIG. 10 is an enlarged view of area "10" in FIG. 1;

FIG. 11 is an enlarged view of area "11" in FIG. 1;

FIG. 12 is an enlarged view of area "12" in FIG. 2; and,

FIG. 13 is an enlarged view of area "13" in FIG. 2.

The broken lines shown in the drawings illustrate portions of the electric bicycle that form no part of the claimed design. The dot-dash lines in FIGS. 1-2 and 9-13 indicate the boundaries of the enlarged views and are used for annotative purpose only. They do not limit or define the scope of the claimed design.

1 Claim, 13 Drawing Sheets
